(57) **CLAIM**

The ornamental design for a femoral hip broach, as shown and described.

DESCRIPTION

FIG. 1 is a front and right side perspective view of a femoral hip broach, showing our new design;

FIG. 2 is an inverted rear and left side perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof; and,

FIG. 9 is an enlarged view of an encircled portion of FIG. 1.

The broken lines of even length depict portions of the femoral hip broach that form no part of the claimed design. The broken line circle consisting of alternating short and long segments in FIG. 1 delineates portions of the femoral hip broach that are shown on an enlarged scale in FIG. 9. The other broken lines consisting of alternating short and long segments represent the bounds of the claimed design.
